Filed Aug. 5, 1960, Ser. No. 61,644

Term of patent 14 years

(Cl. D48—4)

FIG. 2

The shade and fragmentary standard shown in broken lines in FIGURE 1 are for illustrative purposes only.

I claim:

The ornamental design for a lamp mounting unit, as shown and described.
